Light and Light Housing; date unknown but more than one year prior to the filing date of the present application.

Primary Examiner—Angela J Lee

(74) Attorney, Agent, or Firm—Banner & Witcoff, Ltd.

(57) **CLAIM**

The ornamental design for a lighting fixture, as shown and described.

DESCRIPTION

FIG. 1 is a front, left perspective view of a lighting fixture showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front, left perspective view thereof; and,

FIG. 9 is a top, rear, right perspective view thereof.

The uneven-length broken lines represent unclaimed boundaries of the claimed design. The even-length broken lines showing the remainder of the lighting fixture are for environmental purposes only and form no part of the claimed design.

1 Claim, 7 Drawing Sheets
